(57) **CLAIM**

The ornamental design for a display for inner mirror, as shown and described.

DESCRIPTION

FIG. 1 is a front elevational view of a display for inner mirror showing our new design;
 FIG. 2 is a rear elevational view thereof;
 FIG. 3 is a left side view thereof;
 FIG. 4 is a right side view thereof;
 FIG. 5 is a top plan view thereof;
 FIG. 6 is a bottom plan view thereof; and,
 FIG. 7 is a top, front and left side perspective view thereof.
 The oblique shade lines in the drawings represent a reflective surface.
